UNITED STATES PATENT OFFICE.

FRANK THEODORE WILLIAMS, OF MERIDEN, CONNECTICUT.

LAMP-BURNER.

SPECIFICATION forming part of Letters Patent No. 628,424, dated July 4, 1899.

Application filed January 5, 1899. Serial No. 701,236. (No model.)

To all whom it may concern:

Be it known that I, FRANK THEODORE WILLIAMS, a citizen of the United States, residing at Meriden, county of New Haven, State of Connecticut, have invented certain new and useful Improvements in Lamp-Burners, of which the following is a full, clear, and exact description.

My invention relates to an improvement in lamps, especially in those of the central-draft type; and my object is to improve the construction thereof.

Figure 1 is a side elevation, partly in section, of my device. Fig. 2 is a similar view with the parts slightly in different position.

In the preferred form of my invention shown in the drawings, 1 represents the fount of a central-draft lamp, 2 the outer and 3 the inner wick-tubes, the outer wick-tube being slightly higher than the inner one, and 4 a wick moving between the same.

5 is a spreader substantially in the form of a perforated cylinder, fitting in this embodiment within the inner wick-tube and having 25 a flange 6 attached thereto and extending out over the wick and resting thereon, thus connecting the spreader with the wick, in the sense that the spreader is moved by the movement of the wick. As the wick is moved up 30 and down the spreader is moved with it, and when the wick is drawn down inside the wick-tubes this flange 6 will close the opening between the tubes and extinguish the flame. The spreader has an inward bend 12 above 35 its lower end, in this embodiment opposite the flange 6. This gives a greater space between the inner side of the wick and the outside of the spreader than if this spreader were of the same size from the bottom up and 40 allows the vapor and flame to burn from each side of the wick up through a space 13 between flange 6 and the spreader. This results in a saving of the wick, because as the flame can act on each side of the wick the 45 wick need not be turned so high for a given flame as in a construction where the flame can burn from only one side of the wick. This inward bend also provides a space in 50 which air from the spreader can mix with the vapor coming from the inner side of the wick. The flange 7 projects from the upper part of the spreader, and below and close to it is an

other flange 8, and between these flanges is a row of perforations 9.

Projecting up through the inside of the inner tube is a stationary rod 10, passing through a hole in the top of the spreader and carrying at its upper end a stop 11. When the height of the wick is determined which will give the most satisfactory flame, the stop 11 is placed 55 in such a position on the rod 10 that when the wick has been raised to the said height the top of the spreader will come in contact with the stop and the wick cannot be raised higher. This provides a stop for the wick 60 and prevents the wick being turned too high.

Other advantages will appear from an inspection of the disclosure herein, and I do not desire to limit myself to the construction shown and described, as many changes may 70 be made therein without departing from the spirit of my invention.

What I claim is—

1. In a device of the character described in combination, an inner and an outer tube 75 forming between the same a passage in which a wick is adapted to move, a movable spreader and a stationary stop therefor within said inner wick-tube.

2. In a device of the character described an 80 outer and an inner wick-tube, a perforated spreader movable with relation thereto and having an inward bend near the lower part of the same, and a flange carried by said spreader so as to be movable therewith and 85 located near said bend, said spreader and flange having a space between the same for the escape of vapor.

3. In a device of the character described an outer wick-tube, an inner wick-tube, the top 90 of the latter being slightly below that of the former, a perforated spreader located within said outer tube and movable with relation to both said tubes, said spreader carrying a flange adapted to fit within said outer tube 95 and act as an extinguisher, there being a space between the inside of said flange and the outside of said spreader.

4. In a device of the character described in combination a fount adapted to contain a liquid fuel, a wick-tube extending above the same, a second wick-tube smaller than the former also extending above the fount and contained in said outer tube so as to leave a 100

space between the same for the passage of
the wick, a perforated cylindrical spreader,
to supply air to the frame, movable with re-
lation to both of said tubes, a stationary
5 post located within said inner wick-tube and
passing up through the top of said spreader
and having a lateral projection above the top
of said spreader adapted to contact therewith

when said spreader is raised to act as a stop
therefor.

Signed at Meriden, Connecticut, this 3d day
of January, 1899.

FRANK THEODORE WILLIAMS.

Correction in Letters Patent No. 628,424.

It is hereby certified that in Letters Patent No. 628,424, granted July 4, 1899, upon the application of Frank Theodore Williams, of Meriden, Connecticut, for an improvement in "Lamp-Burners," an error appears in the printed specification requiring correction, as follows: In line 3, page 2, the word "frame" should read *flame*; and that the said Letters Patent should be read with this correction therein that the same may conform to the record of the case in the Patent Office.

Signed, countersigned, and sealed this 1st day of August, A. D., 1899.

[SEAL.]

WEBSTER DAVIS,
Assistant Secretary of the Interior.

Countersigned:

A. P. GREELEY,
Acting Commissioner of Patents.
